UNITED STATES PATENT OFFICE

FRANZ PUENING, OF O'HARA TOWNSHIP, ALLEGHENY COUNTY, PENNSYLVANIA

HEATING APPARATUS

Application filed November 23, 1927. Serial No. 235,153.

My invention relates to heating methods and apparatus and particularly to the art of heating furnaces, chambers, retorts, leers and other structures in which it is desired to maintain a uniform temperature throughout a heating chamber that is below the temperature of combustion of ordinary fuels.

An object of my invention is to provide a system of heating in which the currents of hot gases may be reversed in direction by simple and reliable means for effecting such reversals.

Another object of my invention is to provide means for the reversal of heating gases that shall be capable of operation at temperatures which would ordinarily be destructive of the usual mechanical types of reversing mechanisms.

A further object of my invention is to provide reversing mechanism for heating gases that shall be capable of reversing large quantities thereof without unduly increasing the dimensions and cost of the reversing mechanism.

The heating system of the present invention is similar in its general aspects to that shown and described in my Patent No. 1,542,956, granted June 23, 1925. In the patented construction, a piston that is provided with special cooling means operates to actuate the heating gases through the space to be heated in directions that correspond to the direction of the piston. While such mechanism is capable of performing the work for which it is designed, the pistons and the chambers within which they operate are quite bulky when large volumes of gases are reciprocated and their mechanical construction is attended with certain difficulties if the temperature of the gases to be controlled thereby is relatively high.

In accordance with the present invention, I provide a system in which gases are periodically reversed in their direction of flow through the enclosure to be heated. The reversing mechanism comprises in general a series of aspirators which may be, for example, in the form of steam jets for

creating a forced draft in the one or the other direction of flow of the heating gases in accordance with the position of the aspirators. The latter are preferably mounted on a swinging shaft by means of which their position may be reversed at desired times to correspondingly effect the reversal of the flow of gases.

The details of my invention will be described in connection with the accompanying drawings, in which

Figure 1 is a view in horizontal section, taken on line I—I of Fig. 3;

Fig. 2 is an enlarged sectional view of a detail of the swinging shaft and associated parts;

Fig. 3 is a view in vertical section taken on line III—III of Fig. 1;

Fig. 4 is a horizontal sectional view of a portion of the structure of Fig. 1 that is provided with a modified apparatus for actuating and mixing the heating gases;

Fig. 5 is a sectional view of a further modification of the aspirators and associated parts; and

Fig. 6 is a fragmentary sectional view of a modified arrangement for providing orifices for the aspirators.

Referring particularly to Figs. 1, 2 and 3, a heating system constructed in accordance with my invention embodies suitable outer wall 1, which may be of refractory or heat-insulating material that enclose a chamber 2 to be heated, a mixing and reversing chamber 3 and horizontal flues 4 and 5 for connecting opposite sides of the chambers 2 and 3.

The flues 4 and 5 are connected by a horizontal by-pass channel 6 that is, in turn, connected by a duct 7 to a flue 8 extending transversely thereto and adjacent the reversing chamber 3. The flue 8 is connected with a source of heated gases which may be, for example, gases of combustion to be supplied to the central portion of the by-pass channel 6 through the duct 7.

The outer end of the chamber 2 is provided with an outlet opening 9, which communicates with a chamber 10, in which is located any suitable recuperating device 100

such, for example, as a waste heat boiler 11. Waste gases from the chamber 10 escape through a duct 12 and may be conducted to any suitable means for disposing of them 5 such, for example, as a stack (not shown).

The reversing chamber 3 is provided with a curved or arched side wall 14, the central portion of which is of refractory material and the outer or end portions of which are 10 respectively constituted of hollow castings 15 and 16 that are each provided with a series of substantially circular orifices 17 and a relatively large rectangular opening 18. Within the chamber 3 is rotatably mounted a 15 pipe 19 which supports and is connected to a series of smaller pipes 20 and 21 that communicate with corresponding nozzles 22 and 23. The inner ends of the pipes 21 and 22 are perforated, as shown in Fig. 2.

As will be more clearly noted in Fig. 3, the 20 orifices 17 are arranged in two rows in each of the castings, the members of each row being staggered with respect to the other. The nozzles 22 and 23, which correspond in 25 number and arrangement with the orifices 17, register with the orifices of the one or the other casting, depending upon the position of the pipe 19 and its associated parts. The framework constituted by the pipes 20 and 21 supports a rectangular member 24 30 that is adapted to constitute a closure for the opening 18 in the one or the other casting 15 or 16, in accordance with its position.

The pipe 19 is adapted to be supplied 35 with steam from the waste heat boiler 11 by means of a pipe line 26 that is connected to the pipe 19 by a slip joint 27. Each of the hollow castings 15 and 16 is provided with water or other suitable cooling medium 40 by means of a pipe 29 and a pipe line 30, through which the cooling water may circulate. A pipe 31 connects each of the hollow castings to the pipe 26 to provide an outlet for any steam that may be formed 45 within the hollow castings.

The operation of the heating system shown in Figs. 1, 2 and 3 will now be described. It may be assumed that the enclosure 2 or heating chamber is filled with 50 devices or material to be heated and which are represented, by way of example, as cylinders 33. It may be assumed also that the spaces within the walls 1 are filled with hot gases that have been supplied thereto 55 through the flue 8. It may be assumed further that the nozzles 22 and 23 are supplied with steam from the waste heat boiler 11 whereby they constitute aspirators for forcing gases through the orifices 17 and in the 60 direction of the arrows through the flue 4 across the chamber 2 and back through the flue 5 and into the reversing chamber through the orifices 17 and the relatively 65 large opening 18 of casting 16. The open-

ing 18 offers little resistance to the flow of the gases therethrough.

It will be noted that hot gases at a temperature, for example, of 2800° F. are being supplied from the flue 8 into the by-pass 70 channel 6. The hot gases flow in the direction of the arrows, together with the gases traversing the by-pass channel and a portion of the heat of the newly added gases is transferred to an adjacent strata of the older 75 gases until these strata have approximately the temperatures shown in Fig. 1. The gases leaving the chamber 2 have approximately a temperature of 1300° F., which is maintained by the outer strata thereof until they 80 reach the reversing chamber 3. Intermediate strata of these gases may be slightly raised in temperature.

The gases of various temperatures that are received by the reversing chamber 3 are 85 forced through the staggered orifices 17 by the aspirators 22 and 23 on lines that converge, whereby the gases are thoroughly mixed and the resultant temperature is approximately 1600° F., at which they are supplied to the heating chamber 2 and to the 90 by-pass channel 6.

When the operation has continued for a desired period with the aspirators in the position shown in Fig. 1, the pipe 19 is rocked 95 in a clockwise direction, as viewed in Fig. 1, to cause the framework connected thereto to assume the position shown in dotted lines. The pipe 19 is provided with a pinion 34 for connection to a suitable reversing mechanism (not shown). The aspirators now 100 register with the orifices 17 of the casting 16 upon the opposite side of the chamber 3 and the member 24 closes the corresponding opening 18. The conditions are now reversed and the gases flow in the opposite direction, the temperatures of the various strata corresponding substantially to those described above. Since the ducts 7 and 9 for the inlet of hot gases and the outlet of 105 relatively cool gases respectively are located at neutral points with respect to the pressure differentials, the addition of hot gases and the withdrawal of cool gases is not disturbed by the reversal of flow of gases 110 caused by the change in position of the aspirators.

In the structure shown in Fig. 4, the wall surrounding the reversing chamber 35 is provided with two openings 36 and 37 that 115 communicate with the flues 4 and 5. In this construction, a hollow casting 38, that is provided with orifices 39, is carried by pipes 40 and 41 that connect the pipe 19 to the interior of the casting 38 whereby the latter 120 is supplied with steam. The casting 38 is, in turn, connected to a series of nozzles 42 which correspond in character with those shown in Fig. 3 and which register with the 125 corresponding orifices 39.

The operation of the structure shown in Fig. 4 is similar to that previously described except that steam is supplied through the pipe 19, pipes 40 and 41 and casting 38 to the nozzles 42. Steam is thus employed both for cooling the casting 38 and for actuating the heating gases in the direction of the nozzles or aspirators 42. The direction of the heating gases is reversed by rocking the pipe 19 to the position in which the casting 38, with its orifices, registers with the opening 37. The direction of flow of gases is thereupon reversed and the opening 36 constitutes the inlet for the reversing chamber 35.

A modified structure for actuating the heating gases is shown in Fig. 5. Two castings 45 and 46 are provided with orifices, certain of which are in registry and through which gases are actuated by nozzles or aspirators that are respectively connected to the hollow castings. Steam is supplied through pipe 19 and connected pipes 47 and 48. The operation of this form of reversing mechanism is similar in every essential respect to that of the system of Fig. 4, except that a more efficient aspiration of the heating gases is produced by the successive series of orifices in the superposed castings.

In the structure of Fig. 6, a solid member 50, which may be of refractory material, is substituted for the hollow castings of the arrangements previously shown and described. It may be stationary, as in the system of Fig. 1, or it may be movable with the nozzles, as in the arrangement of Fig. 4.

The number of jets or nozzles may be varied as desired, it being apparent that the number is somewhat dependent upon the size and capacity of the apparatus.

In special cases where gas is used as a fuel, the gas and the necessary air for combustion may both be highly compressed and the mixture be blown through the jets instead of steam. In this case, the burning jets of gas flames create the aspirating effect upon the older gases, which are in this manner caused to circulate through the heating chamber and are simultaneously re-heated by the jet flames. In such case, the flues 6, 7 and 8 are not needed. The reversal of the jets and the simultaneous control of the two large openings 18 occurs as before.

Economical operation of the heating system of my invention is accomplished through the simplicity of the mechanism for reversing the direction of flow of gases.

It is further produced through provision and operation of the two large openings through which the gases return into the reversing chamber. These openings are alternately opened and closed simultaneously with the reversal of the jets, so that the circulated heating gases are forced through

narrow jets but once, when leaving the reversing chamber. Their return into this chamber is effected easily and without friction through the one or the other large opening. Economy is further accomplished by the fact that the steam supplied to the jets is produced in the waste heat boiler and in the nozzle castings, the latter being thus kept cool while generating the steam. It is further accomplished by providing for the desired cooling effect, which the steam exerts in the shaft 19 and in the pipes, castings and jets forming the aspirating units, thus protecting these structural devices against overheating and injury, while the steam at the same time becomes superheated, thus assuming a greater volume and passing with increased velocity through the jets.

By reason of the uniformity of temperatures of the heating gases produced by the staggered and converging jets, the devices to be heated within the heating chamber are heated uniformly and are brought to the desired temperature at the same time. The addition of hot gases for maintaining the temperature of the heating gases and the withdrawal of a corresponding volume of gases is not affected by the reversal of gases in the system.

The foregoing and other advantages will be apparent to those skilled in the art relating to heating systems.

I claim as my invention:

1. Heating apparatus comprising an enclosure to be heated and means for reciprocating hot gases through said enclosure, said means comprising aspirators for effecting the flow of gases in accordance with the position of said aspirators.

2. Heating apparatus comprising an enclosure to be heated and means for reciprocating hot gases through said enclosure, said means comprising aspirators for effecting the flow of gases in accordance with the position of said aspirators, and means for shifting the position of said aspirators.

3. Heating apparatus comprising a heating chamber, a second chamber having aspirating devices therein, flues for connecting said chambers at the sides thereof, a by-pass channel for connecting said flues and a channel communicating with said by-pass channel and adapted to supply hot gases thereto.

4. Heating apparatus comprising an enclosure to be heated and means for reciprocating hot gases through said enclosure, said means comprising a plurality of steam jets directed at different angles for thoroughly mixing the gases to be circulated and for creating a forced draft toward said enclosure.

5. Heating apparatus comprising an enclosure to be heated and means for reciprocating hot gases through said enclosure,

5 said means comprising a plurality of steam jets directed at different angles for thoroughly mixing the gases to be circulated and for creating a forced draft toward said enclosure, and means for reversing the position of said steam jets to reverse the flow of gas through said enclosure.

6. Heating apparatus comprising a path 10 for circulating hot gases and means for actuating said gases comprising a plurality of fluid-pressure jets for forcing said gases through orifices at different angles to secure a uniform mixture thereof.

7. Heating apparatus comprising a path 15 for circulating hot gases and means for actuating said gases comprising a plurality of movably mounted fluid-pressure jets whereby the direction of flow of said gases in said path may be reversed.

20 8. Heating apparatus comprising a system for circulating hot gases through an enclosure to be heated, said system having outlet means for withdrawing a portion of the gases being circulated, inlet means for admitting relatively hot gases to replace the gases withdrawn and common means for receiving and intimately mixing the relatively hot and cool gases and for actuating them through said enclosure, said mixing 25 and actuating means being reversible whereby the direction of the gases through said enclosure may be reversed.

9. Heating apparatus comprising an enclosure to be heated, reversible means for 30 circulating hot gases through said enclosure in either of two opposite directions, said enclosure having an outlet through which a portion of the circulated gases may be withdrawn and means for supplying hot gases 35 to said circulating means to replace the gases withdrawn, said circulating means comprising devices for mixing the hot gases with the relatively cooler gases that are to be recirculated.

40 10. Heating apparatus comprising an enclosure to be heated, a chamber, flues for connecting said chamber to said enclosure at opposite sides thereof to provide a path for the circulation of gases through said 45 enclosure, an outlet for a portion of the gases in said path, a by-pass channel for connecting opposite sides of said path, a second channel adapted to supply hot gases to said by-pass channel, and aspirators in said chamber for mixing the gases returned from said enclosure and the gases from said by-pass channel including the hot gases supplied thereto and for actuating the mixed gases through said path.

50 11. Heating apparatus comprising an enclosure to be heated, a chamber, flues for connecting said chamber to said enclosure at opposite sides thereof to provide a path for the circulation of gases through said 55 enclosure, an outlet for a portion of the

gases in said path, a by-pass channel for connecting opposite sides of said path, a second channel adapted to supply hot gases to said by-pass channel, and aspirators in said chamber for mixing the gases returned from 70 said enclosure and the gases from said by-pass channel including the hot gases supplied thereto and for actuating the mixed gases through said path, said aspirators being movably mounted in said chamber 75 whereby the direction of flow of said gases through said enclosure may be periodically reversed.

12. Heating apparatus comprising a device to be heated, means for reciprocating 80 hot gases to and from said device, an enclosure from which gases are actuated and within which they are received, said enclosure having two relatively large openings and means for controlling said openings in 85 accordance with the direction of flow of gases.

13. Heating apparatus comprising a device to be heated, means for reciprocating hot gases to and from said device, an enclosure from which gases are actuated and within which they are received, said enclosure having two relatively large openings and means for actuating gas from said enclosure, said actuating means co-operating 90 with said enclosure to provide relatively small openings for the outgoing gases and a relatively large opening for the incoming gases in either direction of movement of the 95 gases.

14. Heating apparatus comprising a device to be heated, means for reciprocating hot gases to and from said device, a mixing and actuating chamber for the gases to be reciprocated, said chamber having two relatively large openings, and actuating means for said gases, said actuating means being operable to at least partially obstruct the large opening on the outlet side of said chamber while the other opening is unobstructed.

15. Heating apparatus comprising a plurality of fluid-pressure jets for actuating hot gases, a hollow member having relatively small openings through which the hot gases are actuated by said jets and means for operatively connecting said member and said jets to permit fluid under pressure to be supplied through said member to said jets and to be superheated during its passage 115 therethrough.

In testimony whereof, I have hereunto subscribed my name this 22nd day of November, 1927.

FRANZ PUENING. 125
